UNITED STATES PATENT OFFICE.

ANSON P. STEPHENS, OF BROOKLYN, NEW YORK, ASSIGNOR TO HIMSELF, AND MELVIN STEPHENS AND NATHAN STEPHENS, BOTH OF SAME PLACE.

IMPROVED BASE FOR BENCH-VISES.

Specification forming part of Letters Patent No. 96,282, dated October 26, 1869.

To all whom it may concern:

Be it known that I, ANSON P. STEPHENS, of Brooklyn, in the county of Kings and State of New York, have invented and made a new and useful Improved Base for Bench-Vises; and I do hereby declare the following to be a full, clear, and exact description of the said invention, reference being had to the annexed drawings, making part of this specification, wherein—

Figure 1 is a vertical section of said base with a vise thereon, and Fig. 2 is an inverted plan of the said base.

Similar parts are referred to by like letters. Heretofore bench-vises have been made with a turn-table base, upon which the vise may be swung around into the most convenient position for the workman. These turn-tables have usually been made of two flat disks, or else with a rib on one and a groove on the other, the same being circular. In the turn-tables of this character considerable trouble is experienced in turning up the grooves and ribs so as to fit each other. It has to be done by accurate measurement, or else to a pattern. This is too costly for the rough and cheap base of vises, and it is seldom that the rib and groove fit each other. Another difficulty arises in the use of these bases. The chips, filings, and dirt work in between the flat portions of the turn-table and prevent the parts taking a correct bearing upon each other, and the strain laterally in using the vise is thrown upon the clamping-screw.

The nature of my said invention consists in a conical base to be secured to the bench, in combination with a turn-table base to be secured to the vise, and having a conical flange to set over the conical edge of the base, the two being connected by a clamping-screw. By this construction there are no flat surfaces to come together, and chips, filings, or dirt cannot lodge upon the surfaces that come together.

The turning and finishing of the said surfaces are effected with great facility, being simply at a given angle to produce the conical shape, and when the parts are set together they form a strong, steady, and reliable base for the vise, and one that cannot become obstructed or clogged by filings, chips, grease, or similar materials that are frequently found around bench-vises.

In the drawings, *a* is a circular base, with an inclined or conical edge, *2*. Said base is screwed upon the bench shown at *b*.

c is the turn-table base that is to receive upon its upper surface the bench-vise, the parts being connected by screws in any convenient manner. The vise is shown at *d*. Around the base *c* is a pendent flange, *e*, that is circular, with an inclined or conical interior surface that sets upon the surface *2*, the plates or flat portions of the bases *a* and *c* not touching each other.

The clamping-screw *f* is to pass up through a hole in the bench, through the center of the base *a*, and screw into the turn-table *c*. The collar *4* on the screw *f*, taking against the under side of the base *a*, causes the conical surfaces to be drawn together, so as to hold the vise firmly in place when the screw *f* is screwed up.

What I claim, and desire to secure by Letters Patent, is—

The base *a*, with a conical edge, in combination with the turn-table *c*, that is attached to the vise, and provided with a circular flange having an inclined inner surface, to be clamped to the base *a*, and the screw *f*, substantially as and for the purposes set forth.

In witness whereof I have hereunto set my signature this 26th day of March, A. D. 1869.

ANSON P. STEPHENS.
